(57) **CLAIM**

We claim the ornamental design for a combined instrument and music stand, as shown and described.

DESCRIPTION

FIG. 1 is a perspective view of a combined instrument and music stand, showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines showing a musical instrument in FIG. 1 and certain features in FIGS. 6 and 7 depict environmental matter and form no part of the claimed design.
